SAFETY SUPPORTING MEANS FOR BRAKE BEAMS

Filed April 21, 1931

UNITED STATES PATENT OFFICE

SETH A. CRONE, OF EAST ORANGE, NEW JERSEY, ASSIGNOR TO BUFFALO BRAKE BEAM COMPANY, OF NEW YORK, N. Y., A CORPORATION OF NEW YORK

SAFETY SUPPORTING MEANS FOR BRAKE BEAMS

Application filed April 21, 1931. Serial No. 531,706.

The present invention relates to safety supporting means or auxiliary supports for brake beams, and the supporting hangers may be suspended from the bolster of a car 5 truck or from the spring plank, depending upon the construction.

One of the objects of the invention is to provide exceedingly simple and practical means for supporting a safety bar, which is 10 removably secured to outwardly extending foot portions of the hangers, so that the removable fastening means are easy of access.

Another object of the invention is to provide a relatively inexpensive construction 15 whereby the brake beams may be supported in the case of an emergency.

These being among the objects of the present invention, the same consists of certain features of construction and combinations of 20 parts to be hereinafter described and then claimed with reference to the accompanying drawing illustrating a preferred embodiment of the invention and wherein

Figure 1 is a plan of a truck bolster showing 25 the improved supporting means for brake beams supplied thereto;

Fig. 2 is a side elevation thereof showing the improved features;

Fig. 3 is a transverse section of the bolster 30 showing the improved features partly in section; and

Fig. 4 is a plan of a preferred form of safety bar.

Referring to the drawing, the truck 35 bolster 10 has at each side thereof a pair of hanger brackets, one bracket 11 and another 12 in each transverse pair. These hanger brackets are preferably composed of flat sheet metal of proper thickness and each is 40 formed from a strip which is bent to L-shape to provide a vertical leg portion 13 which is secured by rivets 14 to the appropriate side of the truck bolster 10. The lower parts 15, 16 of the two brackets, and which are the 45 angularly bent parts thereof, constitute outwardly extending foot portions.

The outwardly extending foot portions 15, 16 are preferably of the same width as the leg portions 13 of the brackets and are of 50 ample size to provide a considerable bearing

area on each bracket. Holes 17 preferably of rectangular shape are formed in the depending legs 13, at points just above the horizontal bearing surfaces of the foot portions 15, 16.

Said holes 17 are adapted to receive a preferably channeled metal safety bar 18, so that the latter may be supported in horizontal position upon the enlarged bearing surfaces of the outwardly extending foot portions 15, 16. The web of each channel bar 18 rests directly upon the foot portions 15, 16 with the side flanges of the bar extending upwardly. Suitable holes are preformed in the channeled safety bar 18 and in the foot 65 portions 15, 16, and when the holes of the former are in registration with the holes in the latter, headed locking pins 19, 20 are passed through the registering holes, the pins being held in position as by a key or 70 cotter-pin 21. As the foot portions 15, 16 extend outwardly, it is a simple matter to place the locking pins in their position, the heads of the pins being located in the channel 75 of the safety bar 18.

In order to prevent longitudinal movement of the safety bars 18, in an emergency, as when the locking pins may fail for some reason, each of them is preferably formed with projecting tongues or ribs 22, 23 which 80 are struck out from the bar. The free ends of the downwardly inclined tongues 22, 23 engage the inner sides of the ends of the hanger brackets and prevent longitudinal 85 movement of the safety bar. These tongues or lips are preferably cut out of each safety bar before shipment from the mill, and preferably one of them is also struck out so as to require no further operation. The other 90 tongue or lip may be struck out from the safety bar after it has been positioned through the holes 17 in the hanger brackets and properly supported thereby.

Such tongues also enable each safety bar 95 to be positioned and held in place before the locking pins are applied.

Obviously the illustrated and described invention is susceptible to modification as will be apparent to those skilled in the art, 100

without departing from the invention as defined in the appended claims.

What I claim as new is,—

1. In auxiliary supporting means for
5 brake-beams, the combination with a truck
member, of L-shaped hanger brackets, ar-
ranged with the leg portions rigidly secured
to and extending downwardly from the
truck member and the angularly bent lower
10 portions extending outwardly away from
each other to provide foot portions having
horizontal bearing areas of considerable pro-
portions, the leg portions having openings
15 just above the foot portions, a safety bar ex-
tending through the openings and resting on
the foot portions, and means passing through
the safety bar and foot portions for remov-
ably securing the safety bar to the foot por-
tions.
  - 20 2. In auxiliary supporting means for
brake-beams; the combination with a truck
bolster, of L-shaped hanger brackets, ar-
ranged with the leg portions rigidly secured
to and extending downwardly from the truck
25 bolster and the angularly bent lower por-
tions extending outwardly away from each
other to provide foot portions having hori-
zontal bearing areas of considerable propor-
tions, the leg portions having openings just
30 above the foot portions, a safety bar having
a horizontal web, and extending through the
openings and resting on the foot portions,
and means passing downwardly through
such web and the foot portions for remova-
35 bly securing the safety bar to the foot por-
tions.
  3. In auxiliary supporting means for
brake-beams, the combination with a truck
member, of L-shaped hanger brackets, com-
40 posed of flat sheet metal, and arranged with
the leg portions rigidly secured to and ex-
tending downwardly from the truck mem-
ber and the angularly bent lower portions ex-
tending away from the leg portions to pro-
45 vide foot portions having horizontal bear-
ing areas of considerable proportions, the
leg portions having openings just above the
foot portions, the unheaded end of each pin
provided with a movable key, a safety bar
50 extending through the openings and resting

on the foot portions, and relatively large, headed pins for removably securing the safety bar to the foot portions.

4. In auxiliary supporting means for
brake-beams, the combination with a truck
member, of L-shaped hanger brackets, ar-
ranged with the leg portions rigidly secured
to and extending downwardly from the truck
member and the angularly bent lower por-
tions extending outwardly away from each
other to provide foot portions having hori-
zontal bearing areas of considerable propor-
tions, the leg portions having openings just
above the foot portions, a safety bar extend-
ing through the openings and resting on the
foot portions, and removable locking pins
passing downwardly through the foot por-
tions and safety bar to hold it in position. 70

5. In auxiliary supporting means for
brake-beams, the combination with a truck
member, of L-shaped hanger brackets, ar-
ranged with the leg portions rigidly secured
to and extending downwardly from the truck
member and the angularly bent lower por-
tions extending outwardly away from each
other to provide foot portions having hori-
zontal bearing areas of considerable propor-
tions, the leg portions having rectangular
openings just above the foot portions, a 80
channeled safety bar extending through the
openings and having its intermediate web
resting on the foot portions, and means pass-
ing through the web and foot portions for
removably and directly securing the safety
bar to the foot portions. 85

90

95

100

6. In auxiliary supporting means for
brake-beams, the combination with a truck
member, of hanger brackets having leg por-
tions rigidly secured to and extending down-
wardly from the truck member and angular-
ly bent lower portions to provide foot por-
tions having horizontal bearing areas of con-
siderable proportions, the leg portions hav-
ing openings just above the foot portions, a
safety bar extending through the openings
and resting on the foot portions, and remov-
able locking pins passing downwardly
through the foot portions and safety bar to
hold it in position. 105 110
